Primary Examiner — Mary Ann Calabrese(74) *Attorney, Agent, or Firm* — Harness, Dickey & Pierce, P.L.C.(57) **CLAIM**

We claim the ornamental design for a TV receiver with an animated graphical user interface, as shown and described.

DESCRIPTION

FIG. 1 is a first image in a sequence for a TV receiver with an animated graphical user interface showing our new design; FIG. 2 is a second image thereof; and, FIG. 3 is a third image thereof.

The appearance of the transitional image sequentially transitions between the images shown in FIGS. 1-3. The process or period in which one image transitions to another image forms no part of the claimed design.

The broken lines shown in the drawings illustrate portions of the TV, display screen, and graphical user interface that form no part of the claimed design.
